(57) **CLAIM**

The ornamental design for a video conference endpoint microphone, as shown and described.

DESCRIPTION

FIG. 1 is a front perspective view of a video conference endpoint microphone;

FIG. 2 is a front elevation view of the video conference endpoint microphone of FIG. 1;

FIG. 3 is a rear elevation view of the video conference endpoint microphone of FIG. 1;

FIG. 4 is a top plan view of the video conference endpoint microphone of FIG. 1;

FIG. 5 is a bottom plan view of the video conference endpoint microphone of FIG. 1;

FIG. 6 is a left side elevation view of the video conference endpoint microphone of FIG. 1; and,

FIG. 7 is a right side elevation view the video conference endpoint microphone of FIG. 1.

Any portions shown using dashed lines depict environmental subject matter and form no part of the claimed design.
